SAFETY RAZOR

Armand Schreiber, Brooklyn, N. Y.

Application May 31, 1933, Serial No. 673,735

1 Claim. (Cl. 30—61)

The subject of the invention is a new and improved safety razor of the so called Gillette type. The hitherto known ordinary Gillette razors have among other deficiencies the drawback, that they consist of at least three different separate parts: the blade carrying member with the handle on it, the blade clamping member, and the fastening bolt or screw, to which three parts comes the blade itself as a fourth part. As a result of such construction of the ordinary Gillette razors, it happens often, that the one or the other of these different parts gets lost or is dropped and in consequence of this is spoiled or soiled. Besides that, the manipulation of putting together or dismounting such Gillette razors, is a rather slow and difficult task.

The object of the present invention is, to provide an improved safety razor of the Gillette type, which is more easy to be handled, and in which further the danger of some parts being lost or spoiled or soiled in consequence of the separateness of the different parts, is eliminated completely.

In order to obtain this object of the invention and some other advantages to be explained later on, I devised a new and improved razor, the essential feature of which consists therein, that the blade clamping member is brought into a permanent but adjustable connection with the blade carrying member which connection is effected by the means of certain intermediate parts which are arranged at the smaller sides of the razor head, the construction of these different parts being such, that it contains hinges or joints, allowing to swing the blade clamping member either into position above the blade carrying member, or away from the latter, if the blade is to be inserted into or to be removed from the razor head. Another important feature of my new and improved razor consists therein, that the fastening bolt or screw is fixed solidly to the blade clamping member in such position, that the swinging of the blade clamping member into its place over the blade carrying member will bring the fastening bolt or screw opposite to the hole in the blade carrying member, into which it is entered when closing the razor head.

In order to make more clear the invention, I have shown in the drawing two preferred embodiments of my new and improved razor, whereby the

Figs. 1 and 2 illustrate for both embodiments a vertical section through the longitudinal axis of the razor in its opened and in its closed position respectively;

Figs. 3 to 5 are further illustrations of the first embodiment, Fig. 3 showing a partial top view of the blade carrying member, and the Figs. 4 and 5 showing views of the razor head seen from the side, with the blade clamping member in positions lifted vertically above the blade carrying member and swung to the side respectively;

Figs. 6 and 7 are further illustrations of the second embodiment, Fig. 6 showing a side view of the razor head with the blade clamping member swung to the side, and Fig. 7 showing a partial top view of the blade carrying member.

Referring now more in particular to the drawing in the first illustrated embodiment the tubular handle 21, being closed at its lower end by a knob 22 in the usual manner, is provided at its upper end with a shoulder and a slightly conical enlargement 23, which is turnably fitted into a corresponding conical hole in the middle of the blade carrying member, which is shaped similar to the equivalent member in the well-known Gillette apparatus, to be a slightly vaulted rectangular plate 24 with skin protecting teeth along its two longer side edges and with two small blade locating protrusions 25 in the longitudinal axis of its vaulted back. The blade clamping member is likewise shaped in the usual manner as a slightly vaulted rectangular plate 26, having on its concave lower face two recesses 27 corresponding to the two protrusions 25. A screw threaded plug 28 is provided in the middle of the lower face of the plate 26, which plug fits into the internal thread, provided in the upper end 23 of the tubular handle 21. The blade clamping plate 26 has further fixed to it at the ends of its longitudinal axis two downwardly directed arms 30, having each a longitudinal slot 31, through which slot is passed the stem of a headed pin 32, which is screwed into or otherwise fastened to the blade carrying plate 24 at the end of the longitudinal axis of this plate 24. The two smaller sides of the blade carrying plate 24 are preferably provided with conical recesses or notches 33 at the places of the headed pins 32, so that the slanting sides of these notches 33 form movement limiting shoulders or abutments for the swingable arms 30. See Figs. 3 to 5.

From the described construction the manipulation and working of the new razor apparatus is easily understood to be as follows: The blade clamping member is lifted above the blade carrying member as high as the slots 31 and the headed pins 32 will permit it, and then it is swung to the side into the position shown in Fig. 5. Then the razor blade can easily be placed

on the blade carrying member and temporarily held there by the protrusions 25 passing through corresponding holes in the blades. Thereupon the blade clamping member is swung back into the position shown in Fig. 4 and lowered until the threaded plug 28 starts entering into the threaded end 23 of the handle. After that a few turns of the handle 21 in the blade carrying member 24 will pull the plug 28 more down into the threaded hole 23 and will press the clamping plate 26 with the blade below it fast onto the blade carrier plate 24, and the razor is ready to be used. When the shaving work is finished, a few turns of the handle 21 in the opposite direction are sufficient, to lift the clamping plate 26 again above the carrier plate 24, whereupon the clamping plate may be swung again into the position of Fig. 5 and the blade may be removed out of the apparatus.

20 The safety razor of the embodiment shown in the Figs. 6 and 7 is in its essential features built exactly alike to the before described first embodiment, in so far as in this case likewise the handle 34 is turnably mounted within the blade carrying plate 35 and the blade clamping plate 36 is provided with a screw-threaded central plug adapted to enter into the internal thread at the upper end of the handle. Further there are likewise at the smaller sides of the 25 blade clamping plate 36 slotted arms 37, which, by the means of headed pins 38, are pivoted to the smaller sides of the blade carrying plate 35. The only difference in the construction of the razor is, that there are no swing limiting notches in the smaller side faces of the blade carrier plate, but the headed pins or pivots 38 are provided at the plane side face of the plate 35, as it can be seen clearly from the Fig. 7, and the swingable arms 37 are longer, as compared

with those of the first example, so that the blade clamping member 36, when being swung round the pivots 38, clears completely the space above the carrier plate 35, as it is shown in the Fig. 6. The manipulation and working of this razor is 5 exactly the same, as above has been described in detail with reference to the first explained example.

It is understood that the invention is not restricted to the illustrated and above described 10 embodiments, but is to be seen in the hinging of the blade clamping plate to the blade carrier plate by the means of connection links fixed at the smaller sides of the carrier plate and of the clamping plate, in combination with the arrangement of screw threaded parts at the centre 15 of the clamping plate and at the upper end of the handle of the apparatus, which handle is turnably fixed at the blade clamping member.

I claim:

A safety razor of the class described, comprising in combination: a tubular handle; a rectangular blade carrier plate swivelled at its centre on the handle; an internally screw-threaded upper end at the handle; a rectangular blade 25 clamping plate; a screw-threaded plug in the centre of the clamping plate and adapted to enter into the internally threaded end of the handle; longitudinally slotted connection links fixed at the two smaller sides of the clamping 30 plate; headed pivot pins fixed at the two smaller sides of the carrier plate and extending through the slots of the connection links; and shoulders arranged at the smaller sides of the carrier plate at both sides of the connection links, so as to 35 limit the swinging movement of the connecting links round the pivot pins.

ARMAND SCHREIBER.
